UNITED STATES PATENT OFFICE.

JAMES E. DERR, OF CULVER CITY, CALIFORNIA, ASSIGNOR OF ONE-FIFTEENTH TO
ANDREW K. MARTELL, OF LOS ANGELES, CALIFORNIA.

BURGLARPROOF SAFE.

Application filed April 9, 1923. Serial No. 630,802.

To all whom it may concern:

Be it known that I, JAMES E. DERR, a citizen of the United States, residing at Culver City, in the county of Los Angeles and State of California, have invented new and useful Improvements in Burglarproof Safes, of which the following is a specification.

My invention relates to safes and the main object thereof is to provide an improved burglar-proof safe which may be instantly closed mechanically by depressing a pedal or electrically by pressing a switch, when a burglar is detected.

Other objects and advantages will appear hereinafter and while I show herewith and will describe a preferred form of construction, I desire to be understood that I do not limit my invention to such preferred form but that various changes and adaptations may be made therein without departing from the spirit of my invention as herein-after claimed.

Referring to the annexed drawing which forms a part of this specification:

Fig. 1 is a vertical section of my safe in open position.

Fig. 2 is a vertical section of my safe in closed position and before it is set for engaging and holding the cash box slide elevated when the safe is again opened.

Fig. 3 is a view similar to Fig. 2 with the parts set for engaging and holding the cash box slide elevated when the safe is again opened.

Fig. 4 is a side elevation of my safe.

Fig. 5 is a fragmentary vertical section taken on line 5—5 of Fig. 4 showing one of the pedal connections.

Fig. 6 is a longitudinal section of one of the pedal hubs.

Fig. 7 is a cross section of the pedal hub shown in Fig. 5 taken on line 7—7 of said figure.

Fig. 8 is a cross section of the pedal hub taken on line 8—8 of Fig. 6.

In the drawings 1 indicates an outer casing, 2 an inner casing, and 3 a cash box slide which is slidably mounted on the upper end of said inner casing. The outer casing 1 is closed by a lid 4 which is hinged to the upper edge of the rear wall of said casing by hinges 5 so that said lid may swing into the

upper end of said casing against a stop 6 in closed position.

Pins 7 project from the inside of the upper edge of the rear wall of the casing 1 into sockets 8 in the rear edge of the lid 4 to prevent lifting of the rear part of said lid out of the upper end of the casing 1 upon removal of the hinges 5 when the lid is closed.

A link 9 is connected at its upper end to the under side of the lid 4 near its rear edge and at its lower end to the upper end of a sliding vertical rod 10 mounted in bearings 11 and 12 on the inside of the rear wall of casing 1.

A collar 13 is secured on the rod 10 between the bearings 11 and 12 and a spring 14 surrounds the rod 10 between bearing 11 and said collar which spring normally holds the lid 4 in closed position.

A trigger 15 is pivoted at 16 on a bracket 17 secured to the inside of the rear wall of the casing 1 below the bearing 12. Said trigger is formed with arms 18 and 19 and a spring 20 is interposed between arm 19 and a lug 21 on bracket 17 for holding said trigger in position with its arm 18 under the lower end of the rod 10 to hold the lid 4 open as shown in Fig. 1. The lower arm 19 rests adjacent the rear side of casing 2 in the path of travel of the slide 3. The casing 2 is adapted to fit detachably with the outer casing 1 between vertical guides 22 secured to the inside of the vertical walls of the casing 1. The slide 3 is in the form of a box-shaped casing formed with vertical walls 23, which telescope over the upper end of casing 2, and with an upper horizontal wall 24 slightly below the upper ends of the vertical walls, forming a tray 25 in the top of the slide in which rests the cash box 26.

Dogs 30 and 31 are pivotally mounted in the upper part of the front and rear walls of the inner casing 2 within slots 32 and 33 in said walls respectively through which slots said dogs may be swung outwardly into the path of travel of the slide 3. The dog 30 is formed at its pivoted end with a segmental gear 34 which meshes with a pinion 35 journaled in the front wall of casing 2 within slot 33. From the pinion 35 extends an arm 36 and from the dog 31 depends an arm 37 within the casing 2,

through the lower ends of which arms extend a horizontal rod 38, said arms being provided with apertures 39 and 40 respectively to receive said rod.

5 On the outer ends of said rod are secured heads 41 and 42 and collars 43 and 44 are secured on said rod between and near the arms 36 and 37 respectively. A coil spring 45 surrounds the rod 38 between the arm 10 36 and collar 43. A coil spring 46 surrounds the rod 38 between the arm 37 and collar 42. A long lever 47 is pivoted at its lower end at 48 in the lower part of a side wall of the casing 2 and is connected at its upper end to one end of a spring 49, the other end of which spring being connected to a pin 49* in the upper part of the casing 2. The lever 47 is pivoted between its ends at 50 to the rod 15 38 between the collars 43 and 44. On the lower part of the lever 47 is formed a lug 51 to be engaged by a dog 52 which is pivotally mounted in the lower part of a side wall of the casing 2 on a pivot 53.

20 25 A coil spring 54 is interposed between the upper part of the dog 52 and a lug 55 on the inside of a side wall of the casing 2, for normally holding said dog under the lug 51. A solenoid 56 is mounted in the lower part of the casing 2, the core 30 57 of which solenoid being connected to the dog 52.

The pivots 48 and 53 are journaled in bearings 58 in the lower part of a side 35 wall of the casing 2 and extend through said side wall. Pins 59 extend diametrically through the pivots 48 and 53 near the outer ends thereof. Pedals 60 and 61 are each formed with a hub 62, each of 40 which hubs having a longitudinal bore 63, extending from the inner end of the hub, a portion thereof, and with grooves 64—64 and recesses 65—65, said grooves being at opposite sides of said bore and said recesses being at the inner ends of said grooves and near the inner end of said bore. The recesses 65—65 extend diametrically opposite each other from opposite sides of the 45 grooves 64—64.

50 55 The hub 62 of the pedal 60 detachably fits on the pivot 48, said hub extending through an opening 66 in the lower part of a side wall of casing 1 with said pivot fitting in bore 63 and the pin 59 on said 60 pivot resting in one end of the recesses 65—65 away from the inner ends of the grooves 64—64, so that the pedal cannot be removed from the pivot without turning the pedal back until the inner end of the grooves 64—64 registers with said pin 59 to enable the pin to pass out of the pedal hub through said grooves. In placing the hub on said pivot the hub is turned backward so that the grooves 64—64 may 65 receive the pin 59 while the pivot is re-

ceived by the bore 63 and when the hub is slid on the pivot until the pin 59 is opposite the recesses 65—65, the pedal is allowed to turn down so that the pin passes into said recesses and engages the end wall 70 thereof and the wall back of the inner ends of said grooves whereby the pedal is prevented from working off said pivot.

The hub 62 of the pedal 61 is introduced through an opening 67 in the lower part 75 of a side wall of the outer casing 1 and placed on the pivot 53 in the same manner as the hub of the pedal 60 is placed on the pivot 48.

My safe may be secured to the floor by bolts 70 and nuts 71, said bolts extending through the bottom walls of the outer and inner casings 1 and 2 and said nuts screwing on the upper ends of said bolts against the bottom wall of casing 2.

The operation of my safe is as follows:

Assuming the safe to be closed as shown in Fig. 2, the pedal 60 is first depressed which swings the lever 47 to the right until the dog 52 springs under the lug 51 and holds the lever perpendicular as shown in Fig. 3. This movement of said lever moves the rod 38 to the right and causes the collars 42 and 43 to compress the springs 46 and 45 against the arms 37 and 36 respectively. The lid 4 is then swung open on its hinges into vertical position as shown in Fig. 1 against the tension of spring 14, and the slide 3 is lifted until its lower edges escape the dogs 30 and 31, whereupon the dogs under the influence of springs 45 and 46 swing out from the casing 2 under said edges of said slide and support said slide, with the cash box 26 in the top thereof, in elevated position as shown in Fig. 1.

As the slide is first raised its lower edge disengages the trigger arm 19, whereupon the trigger 15 under the influence of its spring 20 is swung to the left until its arm 18 rests under the lower end of rod 10 and holds the door 4 open through said rod and link 9. If a burglar enters the building where the safe is located and at the point of a gun forces the operator to hold up his hands, the operator puts his foot on pedal 61 and depresses it, which disengages dog 52 from lug 51, whereupon the spring 49 swings the lever 47 and the rod 38 to the left, and the heads 41 and 44, engaging the arms 36 and 37, swing the dogs 30 and 31 inwardly out of engagement with the lower edges of the slide 3, which instantly causes the slide with the cash box to drop inside the casing 1, and the lower edge of said slide upon reaching its lowermost position engages the trigger arm 19 and swings the trigger arm 18 out of engagement with the lower end of the rod 10, so that the spring 14 through said pin and link 9 swings the lid 4 closed as illustrated in Fig. 2.

The safe may be closed by the solenoid 56 which is included in an electric circuit 72 which also includes a generator 73 and a switch 74, which may be located in another room or any other suitable place. Instead of depressing pedal 61 the switch 74 may be closed, which will close the circuit 72 and the solenoid 56 will withdraw the dog 52 from under the lug 51 so that the lever 47 and rod 38 will swing to the left under the influence of spring 49, and the heads 41 and 42, engaging arms 36 and 37, will disengage the dogs 30 and 31 from the lower edge of the slide 3 and cause the slide to drop into the casing 1 and the lid 4 to swing closed over said slide as shown in Fig. 2.

Having described my invention I claim:

1. In a safe, a slide mounted in the safe, a door for the safe, means for holding said door open, means for holding said slide elevated in and above the safe, means for releasing said slide holding means from said slide so that said slide will be caused to move back into the safe, said means for holding said door open being engaged and released when said slide is moved back into the safe, and means for closing said door when said holding means is released.

2. In a safe, a slide mounted within the safe, a door for the safe, a sildable rod mounted in the safe, a link connecting said rod and said door, a trigger for engaging said rod to hold said door open, a slide mounted within said safe, means for holding said slide elevated within and above said safe, means for releasing said slide holding means so that said slide will be caused to be withdrawn into the safe and trip said trig-

ger out of engagement with said rod, and means for closing said door when said trigger is tripped.

3. In a safe, a door, a slide, dogs for engaging said slide to hold the same elevated within and above the safe, an arm on one of said dogs, gear teeth on the other dog, a pinion meshing with said teeth, an arm on said pinion, a rod extending through said arms, heads on the ends of said arms, a spring on said rod between said first arm and one of said heads, collars on said rod, a spring on said rod between one of said collars and said other arm, a lever connected to said rod, a pedal connected to said lever, a spring connected to said lever for holding it in position so that said rod springs will hold said dogs inwardly from said slide, a lug on said lever, a dog for engaging said lug when said pedal is depressed and said lever and rod moved to compress said rod springs, said first dogs being adapted to engage said slide under the influence of said rod springs when said slide is elevated, to hold the slide in such position, means for holding said door open, when said slide is elevated, means for tripping said latter dog from said lug so that the said spring connected to said lever will swing the same and move said rod so that the one head and one collar on said rod will engage said arms and trip said first dogs out of engagement with said slide to enable said slide to be withdrawn within the safe, means for releasing said door holding means when said slide is withdrawn within the safe, and means for closing said door when said holding means is released.

JAMES E. DERR.
